UNITED STATES PATENT OFFICE.

EMIL POEPPEL, OF CHICAGO, ILLINOIS.

BEDPOST-FASTENING.

1,106,677.

Specification of Letters Patent. Patented Aug. 11, 1914.

Application filed April 7, 1913. Serial No. 759,389.

To all whom it may concern:

Be it known that I, EMIL POEPPEL, a citizen of the United States of America, and a resident of Chicago, county of Cook, and State of Illinois, have invented certain new and useful Improvements in Bedpost-Fastenings, of which the following is a specification.

This invention relates to means for detachably fastening the horizontal frame members of a bedstead to the bedposts, and the main objects are to provide a corner post fastening for bedsteads, which shall be rigid and strong in character, simple and efficient in construction, inexpensive to manufacture, and convenient to operate for assembling and taking apart the frame.

A specific construction embodying this invention is illustrated in the accompanying drawings, in which—

Figure 1 is a perspective view of one corner of the frame work of a bedstead, as seen from a point adjacent to the top of the diagonally opposite post, and shows a corner post, a fastening member mounted thereon, and the adjacent end of a side rail member held in place by the fastening. Fig. 2 is a somewhat similar view minus the side rail member. Fig. 3 is a side elevation of a pair of corner posts (foot and head) arranged adjacent to each other and held together temporarily in slightly spaced relation, as for exhibition purposes. Fig. 4 is a perspective view of a corner fastening member adapted for detachable mounting on one end of a side rail. Fig. 5 is a plan view of a sheet metal stamping or blank adapted for folding to form a fastening frame or housing member for attachment directly to the bedpost as illustrated in Fig. 2. Fig. 6 is a plan view of a sheet metal stamping or blank adapted for folding to form a detachable end fastening member for a side rail, as illustrated in Fig. 4.

In the construction shown, there is provided a corner post fastening 1 comprising a pair of complementary interlocking members 2 and 3 rigidly attached to the corner post 4 and to a side rail 5 respectively, and adapted to be readily engaged and disengaged with respect to each other for assembling or knocking down the bedstead as desired.

The post engaging member or bracket 2 comprises a frame or housing having on the back side suitable means as outstanding ears

or lugs 6 adapted to lie flat against the bedpost for securing thereto by means of screws or bolts 7, and is formed with a vertical T-slot or groove 8 on its front side to receive a correspondingly formed portion 9 of the complementary fastening member 3 secured to one end of the side rail 5. The post bracket 2 is conveniently formed first as a sheet metal stamping 10, illustrated in Fig. 5, and is then folded into a bracket form of box-like shape as follows: The central or front face part 11 contains a vertical oblong perforation adapted to constitute the T-slot 8 of the said post engaging member or bracket 2, and is flanked by four radiating parts, 12, 13, 14 and 15 adapted to be turned substantially at right angles to the said face portion to form the ends and sides respectively of the box-like bracket 2. The end portions 12 and 13 carry on their outer ends the perforated lugs 6 turned outwardly parallel to the face, and fitted to lie close against the corner post to receive the mounting bolts 7. Both the side parts and the end or top and bottom parts stand perpendicular to the adjacent surface of the post. The end walls 12 and 13 are disposed horizontally, and the side walls 14 and 15 vertically, the latter converging slightly toward the rear sufficiently to stand in radial abutting position square against the outer surface of the cylindrical post 4.

One of the side walls 14 is formed to receive an end of a fastening member 16 for securing the adjacent end of the end rail 17, a slot or opening 18 being formed in the upper edge of the wall 14 therefor. The upper end wall 13 is perforated midway between its side edges for a rivet 19 to secure the inwardly projecting end of the end rail holder 16. The said holder 16 consists of an angle bar, one side or flange of which projects into the post bracket 1 and the other flange being cut away and formed to fit closely against the wall 14 and the opposite end of the holder being perforated for riveting or otherwise splicing to an end rail as indicated by dotted lines in Fig. 1. The adjoining edges of the sides and ends adjacent to the rear of the bracket are interlocked by tongues 21 and grooves 22.

When the post bracket is bent or formed into shape, the T-slot 8 extends over into the top and bottom pieces at each end and is adapted to receive the T-portion or tongue 9 of the side rail holding member 3, the

upper end of the slot in the top plate having short lateral branches disposed just back of the front wall 11 of the finished bracket to accommodate the side arms of the tongue 9, and the bottom of said slot being arranged to stop and seat the lower end of the said tongue member when the said locking members 2 and 3 are engaged. In similar manner the side rail fastening member 3 is first formed as a sheet metal stamping 20, as illustrated in Fig. 6 and then folded and formed into a braced and rigid frame or side rail holder as follows: The horizontal top portion 21 is flanked on one side by a plain flange part 22 which is turned down at right angles, and on its front end by a rectangular face part 23 of substantially square shape which is turned down at right angles and interlocked with the said side flange 22 at their adjacent lower corners by a tongue 24 and groove 25, said face part terminating in a rather long flat brace member 3 turned inwardly and upwardly against the under side of the top 21 where it is fastened by suitable means, as rivets 27.

On the outer surface of the vertical end piece is centrally mounted the tongue 9 for engaging the corresponding groove 8 on the post bracket, and comprising a broad outer plate 28 and a narrow spacing plate 29 disposed symmetrically between said outer plate 28 and the face plate 23, said tongue parts being fastened together and to the plate 23 by suitable clamping means, as rivets 30. The brace 26 is centrally slotted longitudinally to facilitate getting at and heading said rivets 30. The opposite end of the side rail holder from the face and T-catch, is of angle bar shape and is perforated to facilitate splicing to the end of a side rail as indicated in dotted lines in Fig. 1.

The post 4 usually and preferably of hollow cylindrical construction, is provided with an interiorly disposed nut member, as a rectangular bar or plate 31 suitably formed to fit the inner surface of the post and having threaded holes suitably arranged to receive and engage the threaded inner ends of the fastening bolts 7.

The tongue 9 and slot 8 are formed of uniform width and thickness throughout and the tongue is formed substantially uniformly at both ends to permit readily inverting the side rail with respect to top and bottom.

The fastening members are preferably formed substantially uniformly for all four posts to permit interchangeability of posts and to permit assembling the rails irrespective of head and foot or right and left.

The post brackets 2 on account of the end rail holders 16 have to be made in "rights" and "lefts" respectively, though if desired

the side walls 14 and 15 may be made alike by providing a groove in each adapted to receive a holder 16, in which case the holder 16 may be inserted on either side and fastened by the central rivet 19.

To assemble the bedstead the locking or fastening members 2 and 3 may first be attached to the posts and side rails respectively, and the end rails attached to holders 16 on the post brackets 2. Then the side rails and posts are assembled by engaging the corner fastening members 2 and 3 with each other. To take the bedstead apart the operations may be reversed.

In case it is desirable to assemble the head and foot portions of the bedstead in compact arrangement for display purposes, the head and foot posts may be secured together in pairs respectively by the regular end rails, and then in place of the side rails a pair of short links 32 may be bolted to the post brackets 2 to hold the foot and head portions in closely spaced assembled relation, bolts 33 and thumb nuts 34 being provided therefor.

Although but one specific embodiment of this invention has been herein shown and described, it will be understood that numerous details of the construction shown may be altered or omitted without departing from the spirit of this invention as defined by the following claims.

I claim:—

1. In a bedstead, a post bracket of box-like shape adapted for rigid attachment to a corner post and comprising a front wall formed to engage a side rail or side rail holder, a side wall turned back from said front wall and having a notch in its upper edge, and an angle bar having one flange projecting through said notch into the bracket adjacent to the top for attachment thereto and having its other flange depending and abutting against the said side wall.

2. In a device of the class described, an integral sheet metal holder, comprising a top member, an end member turned downwardly at right angles and adapted for engagement with a supporting body, a side member turned downwardly and adapted to brace the said top and end members, and a diagonal brace member continuous with the lower end of said end member and turned inwardly and upwardly therefrom against the under side of the top member where its upper end is rigidly fastened.

Signed at Chicago this 3d day of April 1913.

EMIL POEPPEL.
